UNITED STATES PATENT OFFICE.

ROY D. CONWAY, OF CHATHAM, NEW JERSEY, ASSIGNOR TO WESTERN ELECTRIC COMPANY, INCORPORATED, OF NEW YORK, N. Y., A CORPORATION OF NEW YORK.

TELEPHONE SYSTEM.

Application filed December 29, 1919. Serial No. 348,123.

To all whom it may concern:

Be it known that I, ROY D. CONWAY, a citizen of the United States, residing at Chatham, in the county of Morris, State of New Jersey, have invented certain new and useful Improvements in Telephone Systems, of which the following is a full, clear, concise, and exact description.

This invention relates to an improved method and means for signaling over transmission lines and has particular reference to such method and means as applied to telephone systems.

Toll signaling systems have been devised wherein physical and phantom lines are employed for connecting distant offices or subscribers. In such systems, certain of the lines are employed for the transmission of various signals utilized to signal operators at distance offices and to control the operation of telephone repeaters at intermediate offices. This has been accomplished by the transmission of a single impulse upon the insertion of the plug of a link circuit into the jack of any line when initiating a call.

An object of the invention is to transmit a series of impulses to operate telephone repeaters associated with transmission lines when a change in condition occurs on any one of said lines, and to then transmit another series of impulses in response to another change in condition of said line to identify the line.

Another object is to identify any one of a plurality of transmission lines by the transmission of a series of impulses over a signaling circuit common to said lines and connected to certain of them. The means for accomplishing this object preferably comprises an impulse mechanism including a plurality of groups of relays common to the transmission lines, and another group of relays cooperating with the first named groups to transmit a series of successive impulses, each relay of the other group being individual to one of said lines.

For a complete understanding of the invention, reference is made to the accompanying drawings in which Figs. 1 to 6 inclusive, illustrate diagrammatically a preferred embodiment of the invention; and Fig. 7 is a diagrammatic view illustrating the manner in which Figs. 1 to 6 are to be arranged and also showing a link circuit at each terminating end of the main circuit.

Briefly, the invention is shown as consisting of two distant offices X and Z and an intermediate office Y with physical lines A and C and a phantom line B interconnecting said offices. Each terminating or distant office has associated therewith, an impulse sending mechanism which is operable upon the insertion of a plug into a jack at the office to transmit a series of impulses over a common signaling circuit including conductors simplex to the physical lines A and C. In the present instance, each series consists of five impulses, four of which are of one polarity and the remaining one of a different polarity. When, for example, a call is initiated on any one of the lines at office X, the impulse relay 47 is energized in order that the impulse of a different polarity may be transmitted fourth in the order of succession of the impulses of the series. This fourth impulse is utilized to render effective the telephone repeaters RA, RB, and RC associated with the lines A, B and C at the intermediate office Y. If the line A at office X is taken for use, the impulse relay 17 associated therewith will be energized as soon as the operator actuates the ringing key 3 of a link circuit D, which is connected to jack 10. The operation of this ringing key also initiates a second series of five impulses, four of which are of the same polarity and the remaining one of a different polarity as in the case with the first series of impulses.

However, in the second series, the order of sequence is different in that the first impulse, instead of the fourth is the one of different polarity. At office Z mechanism is provided which is responsive to the second series of impulses and this mechanism includes a relay individual to each of the lines which is operated when ringing current is transmitted over that line by the actuation of the ringing key 3 of the link circuit connected thereto. In the case assumed, where the call is initiated over line A, and the relay 17 is operated by the actuation of the ringing key, the relay 212 individual to the line A at office Z is operated to effect the display of a signal at the operator's position so that the particular line over which the call is initiated is indicated thereat. As long as any one of the lines is in use, the telephone repeaters at the intermediate office will remain effective, but upon the withdrawal of the plugs of the link circuits E at office Z

100

90

105

110

from all of the jacks, a series of impulses is transmitted from office Z to office Y to disable the circuits of the repeaters, this disabling operation being initiated by the energization of relay 257.

It is believed that the invention will now be fully understood from the following detailed description of the operation when considered in connection with the foregoing 10 description.

Operator at office X initiates a call over line circuit A.

The operator at office X desiring to communicate with the operator at office Z over the line circuit A, inserts plug 1 of a link circuit D at office X into jack 10 of line circuit A. Relays 67 and 2 thereupon operate over a circuit traceable from battery 15 through the winding of relay 2, the sleeve contacts of plug 1 and jack 10 and the winding of relay 67 to ground. In response to the operation of relay 67, relays 68 and 69 operate over an obvious circuit but relay 20 69 is slow to operate and release, being indicated as such by the arrows intersecting its armature and pointing in the direction that the armature is slow to move, so that during the interval after relay 68 is operated 25 69 is slow to operate and release, being indicated as such by the arrows intersecting its armature and pointing in the direction that the armature is slow to move, so that during the interval after relay 68 is operated 30 69 is slow to operate and release, being indicated as such by the arrows intersecting its armature and pointing in the direction that the armature is slow to move, so that during the interval after relay 68 is operated 35 69 is slow to operate and release, being indicated as such by the arrows intersecting its armature and pointing in the direction that the armature is slow to move, so that during the interval after relay 68 is operated 40 69 is slow to operate and release, being indicated as such by the arrows intersecting its armature and pointing in the direction that the armature is slow to move, so that during the interval after relay 68 is operated 45 69 is slow to operate and release, being indicated as such by the arrows intersecting its armature and pointing in the direction that the armature is slow to move, so that during the interval after relay 68 is operated 50 69 is slow to operate and release, being indicated as such by the arrows intersecting its armature and pointing in the direction that the armature is slow to move, so that during the interval after relay 68 is operated 55 69 is slow to operate and release, being indicated as such by the arrows intersecting its armature and pointing in the direction that the armature is slow to move, so that during the interval after relay 68 is operated 60 69 is slow to operate and release, being indicated as such by the arrows intersecting its armature and pointing in the direction that the armature is slow to move, so that during the interval after relay 68 is operated 65

The closure of the contact of relay 62 completes the circuit extending from battery through the right-hand normal contact of relay 65 to junction point 58, where it divides one branch of the circuit extending from the junction point through the winding and normal contact of relay 64, and the contact of relay 62 through the interrupter 63 to ground. Relay 64 operates when the circuit is closed through the interrupter 63 and locks over a circuit extending from battery through the right-hand normal contact of relay 65, junction point 58, winding and left-hand alternate contact of relay 64 to ground. Thereupon a circuit is completed when a live segment of interrupter 66 is reached which extends from battery through relay 73, the lower normal contact of relay 17, the junction point 18, the left-hand normal contact of relay 15, the right-hand alternate contact of relay 64, the left-hand normal contact of relay 65 and the inter-

rupter 66 to ground. By the operation of relay 73 the selecting battery 59 is connected across the signaling path. The result of such operation will be described later. Relay 16 operates over a circuit extending from battery through the right-hand normal contact of relay 65, the junction point 58, the winding of relay 16, junction point 18, the left-hand normal contact of relay 15, the right-hand alternate contact of relay 64, the left-hand normal contact of relay 65 and the interrupter 66 to ground. Relay 15 thereupon operates over a circuit extending from battery through the right-hand normal contact of relay 65, junction point 58, the middle alternate contact of relay 16, the middle normal contact of relay 15 and the winding of relay 15 to ground. Relay 15 in operating locks over a circuit extending from battery through the right-hand normal contact of relay 65, the junction point 58, the right-hand alternate contact and winding of relay 15 to ground. By the opening of the left-hand normal contact of relay 15, relay 73 is released, independently of the interrupter 66. When relay 15 is energized, a locking circuit is established for relay 16 extending from battery, the right-hand normal contact of relay 65, the winding and right-hand alternate contact of relay 16, the left-hand alternate contact of relay 15, the right-hand alternate contact of relay 64, the left-hand normal contact of relay 65 and interrupter 66 to ground. This circuit is opened and relay 16 releases when interrupter 66 reaches a non-grounded or dead segment.

Relay 73 again operates when interrupter 66 engages a grounded segment over a circuit extending from battery through the right-hand normal contact of relay 65, junction point 58, winding of relay 73, the lower normal contact of relay 27, the left-hand normal contact of relay 25, the right-hand normal contact of relay 16, the left-hand alternate contact of relay 15, the right-hand alternate contact of relay 64, the left-hand normal contact of relay 65 and the interrupter 66 to ground. Relay 26 also operates over a circuit extending from battery through the right-hand normal contact of relay 65, junction point 58, and the winding of relay 26 to junction point 28 where it joins the circuit just traced for relay 73. The closure of the middle alternate contact of relay 26 causes the operation of relay 25 over a circuit extending from battery through the right-hand normal contact of relay 65, the junction point 58, the middle alternate contact of relay 26, the middle normal contact of relay 25 and the winding of relay 25 to ground. Relay 25 in operating locks over a circuit extending from battery through the right-hand normal contact of relay 65, the junction point 58 and the right-hand alternate contact and wind-

ing of relay 25 to ground. Energization of relay 25 establishes a locking circuit for relay 26 extending from grounded battery right-hand normal contact of relay 65, junction point 58, the winding and right-hand alternate contact of relay 26, the left-hand alternate contact of relay 25, right-hand normal contact of relay 16, left-hand alternate contact of relay 15, right-hand contact 5 alternate of relay 64, left-hand normal contact of relay 65 and the interrupter 66 to ground. This circuit is maintained until the interrupter reaches a non-grounded segment whereupon relay 26 releases. The opening of 10 the left-hand normal contact of relay 25 opens the energizing circuit for relay 73 which then releases.

Upon the interrupter 66 reaching the next grounded segment, relay 73 reoperates over 20 a circuit extending from battery through the right-hand normal contact of relay 65, junction point 58, winding of relay 73, the lower normal contact of relay 37, the left-hand normal contact of relay 35, the right-hand 25 normal contact of relay 26, the left-hand alternate contact of relay 25, the right-hand normal contact of relay 16, the left-hand alternate contact of relay 15, the right-hand alternate contact of relay 64, the left-hand 30 normal contact of relay 65 and the interrupter 66 to ground. Relay 36 also operates over a circuit extending from battery through the right-hand contact of relay 65, junction point 58 and winding of relay 36 to the junction point 38 where it joins the circuit just traced for relay 73. In operating, relay 36 causes the operation of relay 35 over a circuit extending from battery through the right-hand normal contact of relay 65, the 35 middle alternate contact of relay 36 and the middle normal contact and winding of relay 35 to ground. Relay 35 then locks up through its right-hand alternate contact in the same manner as relays 15 and 25. The opening of 40 the left-hand normal contact of relay 35 causes the release of relay 73. When relay 35 is energized a locking circuit is established for relay 36 extending from battery through the right-hand normal contact of relay 65, junction point 58, winding and right-hand alternate contact of relay 36, the left-hand alternate contact of relay 35, right-hand normal contact of relay 26, the left-hand alternate contact of relay 25, the right-hand normal contact of relay 16, the left-hand alternate contact of relay 15, the right-hand alternate contact of relay 64, the left-hand normal contact of relay 65 and the interrupter 66 to ground. This locking circuit for relay 46 is maintained until a non-grounded segment of the interrupter 66 is reached whereupon said relay releases and permanently opens the locking circuit for relay 47 which also releases. The opening 55 of the left-hand normal contact of relay 45 causes the release of relay 74.

When the interrupter 66 engages the next grounded segment, relay 74 operates over a 60 circuit extending from battery through the

right-hand normal contact of relay 65, junction point 58, the winding of relay 74, the lower alternate contact of relay 47, the left-hand normal contact of relay 45, the right-hand normal contact of relay 36, the 70 left-hand alternate contact of relay 35, the right-hand normal contact of relay 26, the left-hand alternate contact of relay 25, the right-hand normal contact of relay 16, the left-hand alternate contact of relay 15, the 75 right-hand alternate contact of relay 64, the left-hand normal contact of relay 65, and the interrupter 66 to ground. Relay 46 also operates over a circuit extending from grounded battery, right-hand normal contact of relay 65, junction point 58, the winding of relay 46, and the junction point 48 where it joins the circuit just traced for relay 74. Energization of relay 46 establishes a circuit for relay 45, extending from 80 battery through the right-hand normal contact of relay 65, the middle alternate contact of relay 46, the middle normal contact and winding of relay 45 to ground. Relay 45 energizes and in so doing opens the previously described locking circuit for relay 47 through its right-hand normal contact. This locking circuit is maintained through the left-hand alternate make-before-break contact of relay 46 until relay 46 deenergizes. Relay 45 is locked over a circuit extending from battery through the right-hand normal contact of relay 65, junction point 58, and the right-hand alternate contact and winding of relay 45 to ground. 85 When relay 45 is operated, a locking circuit is established for relay 46 extending from grounded battery, the right-hand normal contact of relay 65, the winding and right-hand alternate contact of relay 46, the left-hand alternate contact of relay 45, the right-hand normal contact of relay 36, the left-hand alternate contact of relay 35, the right-hand normal contact of relay 26, the left-hand alternate contact of relay 25, the right-hand normal contact of relay 16, the left-hand alternate contact of relay 15, the right-hand alternate contact of relay 64, the left-hand normal contact of relay 65 and the interrupter 66 to ground. This locking circuit for relay 46 is maintained until a non-grounded segment of the interrupter 66 is reached whereupon said relay releases and permanently opens the locking circuit for relay 47 which also releases. The opening 90 of the left-hand normal contact of relay 45 causes the release of relay 74.

When the interrupter reaches the next grounded segment, relay 73 is again operated from the same source of current previously described through the winding of relay 73, lower normal contact of relay 57, the left-hand normal contact of relay 55, the right-hand normal contact of relay 46, the left-hand alternate contact of relay 45, 125 130

the right-hand normal contact of relay 36, the left-hand alternate contact of relay 35, the right-hand normal contact of relay 26, the left-hand alternate contact of relay 25, 5 the right-hand normal contact of relay 16, the left-hand alternate contact of relay 15, the right-hand alternate contact of relay 64, the left-hand normal contact of relay 65 and the interrupter 66 to ground. Relay 56 is 10 also energized in a circuit extending from grounded battery, right-hand normal contact of relay 65, junction point 58, winding of relay 56, and the junction point 75 where it joins the circuit just described for relay 15 73. In energizing, relay 56 establishes a circuit for relay 55 extending from grounded battery the right-hand normal contact of relay 65, the middle alternate contact of relay 56, and the middle normal 20 contact and winding of relay 55 to ground. Relay 55, in energizing causes the release of relay 73 and locks up in a circuit extending from grounded battery, right-hand normal contact of relay 65, and right-hand alternate contact and winding of relay 55 25 to ground. The energization of relay 55, also establishes a locking circuit for relay 56 extending from grounded battery right-hand normal contact of relay 65, the winding and right-hand alternate contact of relay 56, left-hand alternate contact of relay 55, right-hand normal contact of relay 46, the left-hand alternate contact of relay 45, the right-hand normal contact of relay 36, 30 35 the left-hand alternate contact of relay 35, the right-hand normal contact of relay 26, the left-hand alternate contact of relay 25, the right-hand normal contact of relay 16, the left-hand alternate contact of relay 15, 40 45 the right-hand alternate contact of relay 64, the left-hand normal contact of relay 65, and the interrupter 66 to ground. This locking circuit for relay 56 is maintained until the interrupter 66 reaches a non-grounded segment whereupon relay 56 releases.

Upon the interrupter 66 reaching the next grounded segment a circuit is completed from battery through the winding and middle normal contact of relay 65, the right-hand normal contact of relay 56, the left-hand alternate contact of relay 55, the right-hand normal contact of relay 46, the left-hand alternate contact of relay 45, the right-hand normal contact of relay 36, the left-hand alternate contact of relay 35, the right-hand normal contact of relay 26, the left-hand alternate contact of relay 25, the right-hand normal contact of relay 16, the left-hand alternate contact of relay 15, the right-hand alternate contact of relay 64, the left-hand normal contact of relay 65 and the interrupter 66 to ground. Relay 65 is thereby operated and is locked during the engagement of the grounded segment of the inter-

rupter 66 over a circuit extending from battery through the winding and right-hand alternate contact of relay 65 and the grounded segment of interrupter 66 to ground. The opening of the right-hand contact of relay 65 removes the battery from the holding circuits for relays 15, 25, 35, 45, 55 and 64 so that such relays release. Relays 15, 16, 25, 26 etc. now remain in their normal positions until the operator at office X actuates the ringing key 3.

Each operation of relay 73 connects the battery 59 across the signaling path extending from office X to office Y, so that current flows from the positive terminal of battery 59, through the alternate contact of relay 73, the windings of relay 70 in parallel, resistances 71 and 72, the conductor connected to line A extending between office X and office Y, the windings of relay 170 in series, the low and high resistances 171 and 172, the conductor of the line circuit C extending from office Y to office X to the other side of battery 59. The windings of relay 70 are balanced by the resistances 71 and 72, but the direction of current flowing over this circuit is such that relay 170 closes its upper contacts thereby establishing a circuit extending from grounded battery, through the left-hand normal contact of relay 192, the winding of relay 113, the right-hand normal contact of relay 114, the right-hand normal contact of relay 192 and the upper left-hand contact of relay 170 to ground. Relay 113 in operating over this circuit causes the operation of relay 114 over a circuit extending from battery through the left-hand contact of relay 192, the right-hand alternate contact of relay 113 and the left-hand normal contact and winding of relay 114 to ground. Relay 113 then locks up through its winding and left-hand alternate contact and the right-hand alternate contact of relay 114. The opening of the right-hand normal contact of relay 114 opens the energizing circuit of relay 113 but this relay remains in its locked condition until the termination of the impulse, whereupon it releases. Relay 114 locks over a circuit extending from battery through the left-hand normal contact of relay 192 and the left-hand alternate contact and winding of relay 114 to ground.

The second impulse of current received through relay 170 in response to the second operation of relay 73 completes a circuit extending from battery through the left-hand normal contact of relay 192, the winding of relay 123, the right-hand normal contact of relay 124, the left-hand normal contact of relay 113, the right-hand alternate contact of relay 114, the right-hand normal contact of relay 192 and the upper left-hand contact of relay 170 to ground. Relay 123 thereupon operates and causes the operation

of relay 124 over a circuit extending from battery through the left-hand normal contact of relay 192, the right-hand alternate contact of relay 123 and the left-hand normal contact and winding of relay 124 to ground. The operation of relay 124 closes a locking circuit for relay 123 extending through the winding and left-hand alternate contact of said relay and this circuit remains effective throughout the duration of the impulse. Relay 124 is locked over a circuit extending from battery through the left-hand contact of relay 192 and the left-hand alternate contact and winding of relay 124 to ground.

The third impulse of current sent through relay 170 in response to the third operation of relay 73 completes a circuit extending from battery through the left-hand normal contact of relay 192, the winding of relay 133, the right-hand normal contact of relay 134, the left-hand normal contact of relay 123, the right-hand alternate contact of relay 124, the left-hand normal contact of relay 113, the right-hand alternate contact of relay 114, the right-hand normal contact of relay 192 and the upper left-hand contact of relay 170 to ground. Relays 133 and 134 are energized and locked in the same manner as previously described in connection with other similar relays.

The fourth impulse of current received through relay 170 in response to the operation of relay 74, simultaneously with relay 46, is of such direction from the battery that relay 170 closes its lower contacts. A circuit is now completed which extends from battery through the left-hand normal contact of relay 192, the winding of relay 143, the right-hand normal contact of relay 144, the left-hand normal contact of relay 133, the right-hand alternate contact of relay 134, the left-hand normal contact of relay 123, the right-hand alternate contact of relay 124, the left-hand normal contact of relay 113, the right-hand alternate contact of relay 114, the right-hand normal contact of relay 192, the winding of relay 193, and the lower left-hand contact of relay 170 to ground. Relay 143 operates over this circuit. Relay 190 thereupon operates over a circuit extending from battery through the left-hand normal contact of relay 192, the contact of relay 193, the lower normal contact, winding and the upper normal contact of relay 190, the right-hand normal contact of relay 144 where it joins the circuit previously traced for relay 143. Relay 190 in operating locks over a circuit extending from battery through the lower alternate contact, the winding and the middle alternate contact of relay 190 and the contact of relay 191 to ground. Relay 143 in operating causes the operation of relay 144 over a circuit extending from battery through

the left-hand contact of relay 192, the right-hand alternate contact of relay 143 and the left-hand normal contact and winding of relay 144 to ground. Relay 143 momentarily locks up through its winding and left-hand alternate contact until the impulse is completed whereupon said relay releases. The relay 144 remains locked over a circuit which extends from battery through the left-hand normal contact of relay 192, the left-hand alternate contact and winding of relay 144 to ground. The operation of relay 190 completes a ground connection for the filament battery supply circuits of telephone repeaters RA, RB, and RC associated with the line circuits A, B and C respectively, such ground connection being extended through the contact of relay 191 and the upper alternate contact of relay 190.

The fifth impulse of current which is sent over the signaling path and received through the windings of relay 170 due to the operation of relay 73 simultaneously with the operation of relay 56 causes relay 170 to again close its upper contacts thereupon establishing a circuit extending from battery through the left-hand normal contact of relay 192, the winding of relay 153, the right-hand normal contact of relay 154, the left-hand normal contact of relay 143, the right-hand alternate contact of relay 144, the left-hand normal contact of relay 133, the right-hand alternate contact of relay 134, the left-hand normal contact of relay 123, the right-hand alternate contact of relay 124, the left-hand normal contact of relay 113, the right-hand alternate contact of relay 114, the right-hand normal contact of relay 192 and the upper left-hand contact of relay 170 to ground. Relay 153 in operating causes the operation of relay 154 over a circuit extending from battery through the left-hand normal contact of relay 192, the right-hand alternate contact of relay 153 and the left-hand normal contact of winding of relay 154 to ground. Relay 153 is locked up in a circuit extending through its winding and left-hand alternate contact and the middle alternate contact of relay 154 and remains in this condition throughout the duration of the impulse. Relay 154 is locked over a circuit extending from battery through the left-hand normal contact of relay 192 and the left-hand alternate contact and winding of relay 154 to ground. Upon the cessation of the fifth impulse, relay 192 operates over a circuit extending from battery through the winding and middle normal contact of relay 192, the right-hand normal contact of relay 153, the middle alternate contact of relay 154, the normal contact of relay 143, the right-hand alternate contact of relay 144, the normal contact of relay 133, the right-hand alternate contact of relay 134, the normal contact of relay 123, the right-

hand alternate contact of relay 124, the normal contact of relay 113, the right-hand alternate contact of relay 114, the right-hand alternate contact of relay 154 and the left-hand normal contact of relay 153 to ground. The opening of the left-hand normal contact of relay 192 causes the release of relays 114, 124, 134, 144 and 154, and the opening of the right-hand alternate contacts of said relays disables the operating circuit of relay 192, which thereupon returns to normal.

The closure of the upper contact of relay 170, in response to the first impulse transmitted by the operation of relay 73 when plug 1 is inserted in jack 10, also completes a circuit from battery through the winding of relay 183 and the right-hand upper contact of relay 170 to ground. The second, third and fifth impulses transmitted also operate relay 183 over the same circuit, but the fourth or positive impulse sent operates relay 184 over a circuit extending from battery through the winding of said relay and the right-hand lower contact of relay 170 to ground. Upon each energization of relay 183, battery 159' is connected across the line over a circuit extending through the alternate contact of relay 183, the windings of relay 180 in parallel, the resistances 181 and 182, the simplex conductors of line circuit A extending between office Y and office Z, the low and high resistances 271 and 272, the windings of relay 270 in series, the simplex conductors of line circuit C extending between office Z and office Y to the other pole of battery 159'. The strength of the current and the direction of flow thereof has no effect upon relay 180 but operates relay 270 to close its upper contact. Upon the first closure of the upper contact of relay 270, a circuit is established extending from grounded battery, the right-hand normal contact of relay 260, the winding of relay 213, the left-hand normal contact of relay 214, the left-hand normal contact of relay 260 and the upper contact of relay 270 to ground. Relay 213 energizes in this circuit and establishes a circuit for relay 214 extending from ground through the winding and right-hand normal contact thereof, the left-hand alternate contact of relay 213 and the right-hand normal contact of relay 260 to grounded battery. Upon the energization of relay 214 a temporary locking circuit is established for relay 213 which lasts throughout the duration of the impulse, said circuit extending from grounded battery through the right-hand normal contact of relay 260, the winding and right-hand alternate contact of relay 213, the left-hand alternate contact of relay 214, the left-hand normal contact of relay 260 and the upper contact of relay 270 to ground. Relay 214 locks up through its winding and right-hand alternate contact to grounded battery at the

right-hand normal contact of relay 260. At the termination of the impulse, the locking circuit for relay 213 is opened and said relay releases. The second, third and fifth impulses operate to successively energize relays 223, 224, 233, 234, 253 and 254, in the same manner as described in connection with relays 123, 124, etc. The fourth impulse, which causes the energization of relay 184, establishes a circuit extending from positive pole of battery 169' over the simplex conductors of line circuit A extending from office Y to office Z, the resistances 271 and 272, the windings of relay 270, the simplex conductors of line circuit C extending between office Z and office Y, the windings of relay 180, associated resistances 181 and 182, normal contact of relay 183 and the contact of relay 184 to the other pole of battery. The strength and direction of flow of the current in this circuit has no effect upon relay 180, the windings thereof being balanced by the resistances 181 and 182, but relay 270 operates to close its lower contact. A circuit is then established extending from grounded battery, the right-hand normal contact of relay 260, the winding of relay 243, the left-hand normal contact of relay 244, the normal contact of relay 233, the left-hand alternate contact of relay 234, the normal contact of relay 223, the left-hand alternate contact of relay 224, the normal contact of relay 213, the left-hand alternate contact of relay 214, the left-hand normal contact of relay 260, the winding of relay 261 and the lower contact of relay 270 to ground. The relays 243 and 261 are energized in this circuit but the energization of relay 261 at this time has no effect upon the circuit. The energization of relay 243 causes the energization of relay 244 and the establishment of a locking circuit therefor, in the same manner as described in connection with relay 214. At the termination of the fifth impulse relay 260 is energized by the circuit extending from battery through the winding and middle normal contact of relay 260, the left-hand normal contact of relay 253, the middle alternate contact of relay 254, from thence through contacts of relays 243, 244, 233, 234, 223, 224, 213, 214 as before described, the left-hand alternate contact of relay 254 and the right-hand normal contact of relay 253 to ground. Relay 260 energizes and causes the release of relays 214, 224, 234, 244 and 254 and then restores to normal.

The entire foregoing description of the operation takes place immediately upon the insertion of plug 1 into the jack 10, regardless of whether or not the operator has operated her ringing key 3. When the operator actuates the ringing key at any time after the plug 1 is inserted into the jack, the relay 17 is operated over a circuit extending from

the source of alternating current through the lower alternate contact of key 3, the ring contacts of plug 1 and jack 10, the lower normal contact of relay 12, the upper winding of relay 17, the condenser 19, the upper normal contact of relay 12, the tip contacts of jack 10 and plug 1, and the upper alternate contact of key 3 to ground. Relay 17 energizes and locks in a circuit extending 10 from ground through its lower winding and upper alternate contact, the normal left-hand contact of relay 16, the normal right-hand contact of relay 15, the winding of relay 62 and the right-hand normal contact of 15 relay 65 to grounded battery. Relay 62 energizes in this circuit and through the interrupter 63 establishes a circuit for relay 64, as previously described, whereupon relay 64 locks up. Upon the energization of relay 20 64, a circuit is established from grounded battery through the right-hand normal contact of relay 65, junction point 58, the winding of relay 16, junction point 18, the left-hand normal contact of relay 15, the right-hand alternate contact of relay 64, the left-hand normal contact of relay 65 and a grounded segment of interrupter 66 to ground. At the same time another circuit is 25 established from the same source of current through the winding of relay 74, the lower alternate contact of relay 17 to the junction point 18 where it joins the previously described circuit for relay 16. The energization of relay 16 initiates another operation 30 of the chain of relays 15, 16, 25 and 26, etc., which is the same in all respects as the previous operation of this chain of relays with the exception that relay 74 is operated upon the first impulse instead of the fourth. 35 When relay 16 releases and relay 15 locks in this series of operations, the locking circuit for relay 17 is opened. The energization of relay 74 connects battery 59' across the line to energize the polarized relay 170, which 40 first closes its lower contacts and then its upper contacts in response to the successive energizations of relay 73 following the energization of relay 74. The energization of relay 170 initiates the same operation, as 45 previously described in connection with relays 113, 114, 123, 124, etc., but the operation of these relays has no effect upon the repeater circuits since relay 190 has been energized and locked in the manner previously 50 described. In response to the first energization of relay 170 when the same closes its lower contacts, the circuit is again established for relay 184. This connects battery 169' across the signaling circuit 55 whereby relay 270 is energized as previously to close its lower contact. Relays 213, 214, 223, 224, etc., having been released after the termination of the fifth impulse of the first series, a circuit is now established from 60 grounded battery through the right-hand 65 normal contact of relay 260, the winding of relay 213, the left-hand normal contact of relay 214, the left-hand normal contact of relay 260, the winding of relay 261, and the contact of relay 270 to ground. Relays 213 and 261 70 energize in this circuit and the former relay again establishes a circuit for relay 214, as previously described, whereupon relay 214 again locks up. Upon the energization of relays 213, 214 and 261, a circuit is established from grounded battery through the right-hand normal contact of relay 260, the contact of relay 261, the winding of relay 212, the lower right-hand alternate contact of relay 213, the left-hand alternate contact of relay 214, the left-hand normal contact of relay 260, the winding of relay 261 and the lower contact of relay 270 to ground. Relay 212 energizes and remains in this condition 75 throughout the duration of the impulse. 80 By attracting its armatures, relay 212 establishes a circuit for drop or signal 211 extending from the source of alternating current through the lower alternate contact of relay 212, the winding of drop 211 and the upper alternate contact of relay 212 to ground. Drop 211 upon energizing displays a signal to indicate to the operator at office Z that a connection is desired over the line 85 A. The succeeding impulses of the second series initiated at office X operate through the relay 183 to energize relays 223, 224, 233, 234, etc., in the same manner as previously described in connection with these relays, but this operation has no effect upon the 90 circuit. At the end of the impulses, relay 260 again operates as previously described to restore relays 214, 224, 234, 244 and 254. In response to the signal displayed at the operator's position, a plug 201 of a link circuit E 105 at office Z is inserted into jack 210, thereby disconnecting the winding of drop 211 from the line A and causing the operation of relays 202 and 267 over a circuit extending from battery through the winding of relay 110 202, sleeve contacts of plug 201 and jack 210, and the winding of relay 267 to ground. In response to the operation of relay 267, relays 268 and 269 operate, and since relay 269 is slow to operate, a temporary circuit is 115 established for relay 247 which extends from battery through the alternate contact of relay 268, the upper winding of relay 247 and the normal contact of relay 269 to ground. Relay 247 in operating locks over a circuit 120 extending from battery at the left-hand normal contact of relay 265 through the winding of relay 262, the left-hand normal contact of relay 245, the right-hand normal contact of relay 246 and the middle alternate contact, the lower winding and the upper alternate contact of relay 247 to ground. In 125 operating, relay 262 prepares a circuit for relay 264 so that when the interrupter 263 engages the next succeeding grounded seg- 130

ment, relay 264 operates over a circuit extending from battery through the right-hand normal contact of relay 265, the junction point 258, the winding and normal contact of relay 264, the contact of relay 262 and the grounded segment of relay 263 to ground. A circuit is also completed extending from battery through the right-hand normal contact of relay 265, the junction point 258, the right-hand normal contact of relay 215, the winding of relay 216, the left-hand alternate contact of relay 264, the right-hand normal contact of relay 265 and upon the engagement of a grounded segment through the interrupter 266 to ground. Relays 215, 226, 225, 236, 235, 246, 245, 256, 255 and 265 thereupon operate in response to the successive engagements of the grounded segments of the impulse-sending interrupter 263 in a manner similar to that described for the first series of operations of relays 16, 15, 26, 25, 36, 35, 46, 45, 56, 55 and 65 at office X in initiating a call. The impulses impressed upon the signaling circuit comprising the simplex conductors of the line circuits A and C, extending from office Z to office Y, in response to the operation of relays 273 and 274 caused by the stepping operation of the other relays, causes the operation of polar relay 180 in a manner similar to that described for polar relay 170 in response to the similar series of impulses transmitted from office X to office Y. However, the modified impulse which is transmitted by the operation of relay 274 simultaneously with relay 246, will produce no other effect upon the system than the usual effect produced upon the stepping relays 143 and 144, since the filament battery supply circuits of repeaters RA, RB, and RC are controlled independently of such relays by the locking of relay 190 through the contact of relay 191 in response to the transmission of the signals from office X to office Y. Therefore, relays 113, 114, 123, 124, 133, 134, 143, 144, 153, 154 and 192 operate as previously described. The operation of relay 180 also causes the operation of relays 173 and 174 to repeat the series of impulses into the circuit including simplex conductors of the line circuits A and C, extending from office Y to office X, and in response to such impulses relay 70 operates to cause relays 13, 14, 23, 24, 33, 34, 43, 44, 53, 54, 60 and 61 to operate in a manner similar to that described in connection with the response of relays 213, 214, 223, 224, 233, 234, 243, 244, 253, 254, 260 and 261 upon the receipt of the signaling impulses from office X. However, relay 12 does not operate in the manner described for relay 212 in the second series of operations of stepping relays at office Z, since the ringing key 203 in the link circuit E, associated with the line circuit A has not been actuated.

By the actuation of the listening keys 4 and 204 respectively of circuits D and E, associated with the line circuit A, a communication channel is established between the operators at said offices for the line circuit A. 70

Operator at office X initiates a call over phantom line circuit B.

The operator at office X desiring to contemporaneously extend a call from office X to office Z over phantom circuit B, inserts plug 1 of another link circuit D at office X into jack 20 of the line circuit B, thereby causing the operation of relay 2 over a circuit extending from battery through the winding of relay 2, the sleeve contacts of plug 1 and jack 20 where it joins the circuit traced for relay 67 in connection with the initiation of the call over line circuit A. Relay 67 having operated in connection with the previous call no material effect is produced upon the system at this time. The operator at office X thereupon actuates ringing key 3 associated with the selected link circuit D completing a circuit extending from the source of alternating current through the lower alternate contact of key 3, the ring contacts of plug 1 and jack 20, the lower normal contact of relay 22, the upper winding of relay 27, the condenser 29, the upper normal contact of relay 22, the tip contacts of jack 20 and plug 1 and the upper alternate contact of key 3 to ground. Relay 27 thereupon operates, the opening of the upper and middle normal contacts thereof disconnecting the line terminal from the line circuit extending to the distant offices, and in closing the upper alternate contact of relay 27 establishes a locking circuit for itself which extends from battery through the right-hand normal contact of relay 65, the winding of relay 62, the right-hand normal contact of relay 25, the left-hand normal contact of relay 26 and the upper alternate contact and lower winding of relay 27 to ground. The operation of relay 62, as in the previous instance, prepares a circuit including the interrupter 63, so that when such interrupter reaches the grounded segment relay 64 operates over the circuit previously traced therefor to include the impulse-sending interrupter 66 in circuit with relay 16, causing the operation of the latter relay and the sequence of operations of relays 15, 26, 25, 36, 35, 46, 45, 56 and 55 as previously described in connection with the initiation of a call over line circuit A. The locking circuit for relay 27 is opened at the termination of the second impulse by the release of relay 26 and continued energization of relay 25. Relays 73 and 74 respond to this series of operations in a manner similar to that previously described, excepting that relay 74 instead of 130

relay 73 operates simultaneously with relay 26, thereby causing a reversed current or positive impulse to be transmitted over the circuit including simplex conductors of line circuits A and C, extending from office X to office Y. At office Y relay 170 responds to such impulses and no effect is produced upon the apparatus located at office Y, except the stepping operation of relays 113, 114, 123, 124, 133, 134, 143, 144, 153, 154 and the operation of relay 192 to release the locked relays. However, the impulses are repeated by the relay 170 cooperating with relays 183 and 184 into the circuit including the simplex conductors of line circuits A and C, extending from office Y to office Z, in a manner similar to that previously described, excepting that relay 184 is operated instead of relay 183 in response to the second impulse which is sent by relay 74. These impulses are received by relay 270 which operates in response to the first impulse to close a circuit extending from battery through the right-hand contact of relay 260, the winding of relay 213, the left-hand normal contact of relay 214, the left-hand normal contact of relay 260 and the upper contact of relay 270 to ground. The current flowing through this temporary circuit causes the operation of relay 213, which in turn causes the operation of relay 214 in a manner similar to that described in connection with the call which was extended over line circuit A. However, due to the reversed polarity of the second impulse being transmitted from office X through office Y, relay 270 in response to such second impulse closes its lower contact thereupon causing the operation of relay 223 in the manner similar to that previously described, but also causes the operation of relay 261 over a circuit extending from battery through the right-hand contact of relay 260, the winding of relay 223, the left-hand normal contact of relay 224, the right-hand normal contact of relay 213, the left-hand alternate contact of relay 214, the left-hand normal contact of relay 260, the winding of relay 261 and the lower contact of relay 270 to ground. Relay 261 completes a circuit for causing the operation of relay 222 which extends from battery through the right-hand normal contact of relay 260, the contact of relay 261 and the winding of relay 222 to the lower right-hand alternate contact of relay 223 where it joins the circuit previously traced for the latter relay which is locked during the transmission of the impulse. Therefore, relay 222 is temporarily operated during the transmission of the impulse and completes a circuit extending from the source of alternating current through the lower alternate contact of relay 222, the lower normal contact of jack 220, the winding of signaling

device or drop 221, the upper normal contact of jack 220 and the upper alternate contact of relay 222 to ground. Signaling device 221 thereupon operates indicating to the operator at office Z that a call is being extended over the line circuit B. In response to the display of the signal produced by the device 221, the operator at office Z inserts plug 201 of another link circuit E thereat into the jack 220, thus, as in the previous instance, removing the signaling device from the control of the line circuit and causing the operation of the sleeve relay 202. By the actuation of the listening keys 4 and 204 of the link circuits D and E respectively which are associated with the line circuit B, the operators may communicate with each other over such line circuit.

Operator at office X initiates a call over line circuit C.

The operator at office X desiring to contemporaneously extend a call over line circuit C, inserts the plug 1 of a third link circuit D thereat into the jack 30, thereby causing the operation of relay 2 as in the case of the call being extended from the line circuit B. The ringing key 3 of such link circuit B being actuated, a circuit is completed extending from the source of alternating current through the lower alternate contact of ringing key 3 of the selected link circuit D, the ring contacts of plug 1 and jack 30, the lower normal contact of relay 32, the upper winding of relay 37, the condenser 39, the upper normal contact of relay 32, the tip contacts of jack 30 and plug 1 and the upper alternate contact of key 3 to ground. Relay 37 operates in response to the current flowing over such circuit and locks in an operated condition over a circuit extending from battery through the right-hand normal contact of relay 65, the winding of relay 62, the right-hand normal contact of relay 35, the left-hand normal contact of relay 36, the upper alternate contact and lower winding of relay 37 to ground. Relay 37 remains locked throughout the duration of the third impulse. The operation of relay 37 disconnects the line terminal from the line circuit extending to the distant offices. As in the previous instance, relay 62 operates to include the interrupter 63 in circuit with the relay 64, so that the impulse-sending interrupter 66 is included in circuit with the relay 16 to cause the sequence of operations of relays 15, 26, 25, 36, 35, 46, 45, 56, 55 and 65 as previously described, such sequence of operations causing the operations of relays 73 and 74 as described in connection with the initiation of the call over line circuit A, except that on the third impulse relay 74 instead of relay 73 operates simultaneously with relay 36, thereby causing a re-

- versed current impulse to be transmitted over the signaling circuit including the simplex conductors of line circuits A and C, extending from office X to office Y. These impulses being received at office Y produce no material effect thereat, and are repeated in a manner similar to that previously described to the signaling circuit including the simplex conductors of line circuits 5
- 10 A and C, extending from office Y to office Z. Upon the receipt of these impulses at office Z, relay 270 operates, as described in connection with the receipt of the call from office X, over line circuit A, except that in 15 response to the third impulse such relay closes its lower contact so that although relays 213, 214, 223, 224, 233, 234, 243, 244, 253, 254 and 260 operate as previously described in connection with the first series of 20 impulses received in connection with the initiation of the call over the line circuit A, when the third impulse is reached in the series, relay 261 operates over a circuit extending from battery through the right- 25 hand normal contact of relay 260, the winding of relay 233, the left-hand normal contact of relay 234, the right-hand normal contact of relay 223, the left-hand alternate contact of relay 224, the right-hand normal 30 contact of relay 213, the left-hand alternate contact of relay 214, the left-hand normal contact of relay 260, winding of relay 261, and the lower contact of relay 270 to ground. In response to the operation of relay 261, 35 relay 232 is momentarily operated over a circuit extending from battery through the right-hand normal contact of relay 260, the contact of relay 261, the winding of relay 232 to the lower right-hand alternate contact of relay 233 where it joins the operating 40 circuit of relay 233. The operation of relay 232 establishes a temporary circuit which extends from a source of alternating current through the lower alternate contact of relay 232, the lower normal contact of jack 230, the winding of signaling device 231, the upper normal contact of jack 230 and the upper alternate contact of relay 232 to ground. Relays 243, 244, 253, 254 and 45 50 260 thereupon operate as in the previous instances. In response to the signal displayed by the device 231, the operator at office Z inserts the plug 201 of another link circuit E at office Z into jack 230, thereby removing the winding of the line signaling device 231 from connection with the line and causing the operation of relay 202 in the connected link circuit as in the previous cases. 55
- 60 *Operator at office Z transmits disconnect signals to operator at office X.*
- Upon the completion of the conversation over line circuit A, the operator at office Z actuates ringing key 203 of the link circuit 65 E thereat, causing the operation of ringing response relay 217 over a circuit extending from a source of alternating current through the lower alternate contact of key 203, the ring contacts of plug 201 and jack 210, the lower normal contact of relay 212, the upper winding of relay 217, the condenser 219, the upper normal contact of relay 212, the tip contacts of jack 210 and plug 201 and the upper alternate contact of key 203 to ground. In operating, relay 217 75 disconnects the conductors leading to the tip and ring contacts of the jack from the outgoing line conductors and locks over a circuit extending from battery through the left-hand normal contact of relay 265, winding of relay 262, the left-hand normal contact of relay 215, the right-hand normal contact of relay 216 and the upper alternate contact and lower winding of relay 217 to ground. In operating, relay 262 prepares 80 a circuit including the interrupter 263 in circuit with the winding of relay 264 so that when a grounded segment of the interrupter is reached, relay 264 operates over a circuit extending from grounded battery, through the left-hand normal contact of relay 265, the winding and normal contact of relay 264, the contact of relay 262, and the interrupter 263 to ground. In operating, relay 264 locks over a circuit extending from 85 grounded battery, through the left-hand normal contact of relay 265, winding and right-hand alternate contact of relay 264 to ground. A circuit is thereupon prepared including the impulse sending interrupter 266 in circuit with the various stepping relays so that when the first grounded segment of interrupter 266 is reached, relay 274 operates over a circuit extending from 90 grounded battery, left-hand normal contact of relay 265, junction point 258, winding of relay 274, lower alternate contact of relay 217, right-hand normal contact of relay 215, left-hand alternate contact of relay 264, right-hand normal contact of relay 265, and the interrupter 266 to ground. A circuit is 95 simultaneously established for relay 216, extending from grounded battery, left-hand normal contact of relay 265, junction point 258, winding of relay 216 and the junction point 218 where it joins the circuit previously traced for relay 274. Relay 216 energizes and establishes a circuit for relay 215, extending from grounded battery, through the left-hand normal contact of relay 265, middle alternate contact of relay 216, the middle normal contact and winding of relay 215 to ground. Relay 215 energizes and establishes a locking circuit for relay 216 extending through its winding and left-hand alternate contact and the right-hand alternate contact of relay 215 to ground through the interrupter 266. Relay 215 locks in a circuit extending from grounded battery 100 through the left-hand normal contact of re- 105

- 130

lay 265, left-hand alternate contact and winding of relay 215 to ground. When the interrupter 266 disengages the grounded segment, relay 216 releases but relay 215 remains locked in an operated condition over the circuit just traced therefor. Relay 274 releases upon the release of relay 216 but during the period in which relay 274 is operated, a circuit is completed from one pole of battery 269' through the alternate contact of relay 274, the normal contact of relay 273, the windings of relay 270 in parallel, the simplex conductors of line circuit C extending from office Z to office Y, the windings of relay 180 in series, the simplex conductors connected to line circuit A extending from office Y to office Z, and to the other side of the battery 269'. The low and high resistances 271 and 272 in this circuit balance the windings of relay 270 and this relay, therefore, does not operate but the circuit passing through the windings of relay 180 in series, is unbalanced by the resistances 181 and 182, and relay 180, therefore, operates to close its lower contacts. Upon the release of relay 216, relay 217 releases to complete the continuity of the line conductors and relay 226 thereupon operates when the impulse-sending interrupter 266 reaches the next grounded segment, the circuit for such relay being traceable from battery through the left-hand normal contact of relay 265, the winding of relay 226, the right-hand normal contact of relay 225, the left-hand normal contact of relay 216, the right-hand alternate contact of relay 215, the left-hand alternate contact of relay 264, the right-hand normal contact of relay 265 and the interrupter 266 to ground. Relay 273 also operates at this time over a circuit extending from battery through the left-hand normal contact of relay 265, the winding of relay 273, the lower normal contact of relay 227 to the right-hand normal contact of relay 225 where it joins the circuit just traced for relay 226. The operation of relay 273 connects battery 259 across the signaling circuit extending from office Z to office Y, thereby providing the reversed direction of current flowing in such signaling circuit. Relay 226 in operating causes the operation of relay 225 over a circuit extending from battery through the left-hand normal contact of relay 265, the middle alternate contact of relay 226 and the middle normal contact and winding of relay 225 to ground. Relay 225 then locks in a circuit through its winding and left-hand alternate contact. Relay 226 thereupon locks over a circuit extending from battery through the left-hand normal contact of relay 265, the winding and left-hand alternate contact of relay 226, the right-hand alternate contact of relay 225, the left-hand normal contact of relay 216, the right-hand alternate contact of relay 235, the left-hand normal contact of relay 264, the right-hand normal contact of relay 265 and the interrupter 266 to ground. When the interrupter 266 disengages the grounded segment thereof, relay 236 is released but relay 225 remains locked over a circuit traced therefor.

Relay 236 operates when the interrupter 266 engages the next grounded segment, the operating circuit for such relay being established from battery through the left-hand normal contact of relay 265, the winding of relay 236, the right-hand normal contact of relay 235, the left-hand normal contact of relay 226, the right-hand alternate contact of relay 225, the left-hand normal contact of relay 216, the right-hand alternate contact of relay 215, the left-hand alternate contact of relay 264, the right-hand normal contact of relay 265 and the interrupter 266 to ground. Relay 273 also operates over a circuit extending from battery through the left-hand normal contact of relay 265, the windings of relay 273, the lower normal contact of relay 237 and the right-hand normal contact of relay 235 where it joins the circuit traced for relay 236. Relay 235 thereupon operates over a circuit established from battery through the left-hand normal contact of relay 265, the middle alternate contact of relay 236 and the middle normal contact and winding of relay 235 to ground. Relay 235 in operating locks over a circuit extending from battery through the left-hand normal contact of relay 265, the left-hand alternate contact and winding of relay 235 to ground. Relay 236 thereupon locks over a circuit extending from battery through the left-hand normal contact of relay 265, the winding and left-hand alternate contact of relay 236, the right-hand alternate contact of relay 235, the left-hand normal contact of relay 226, the right-hand alternate contact of relay 225, the left-hand normal contact of relay 216, the right-hand alternate contact of relay 215, the left-hand alternate contact of relay 264, the right-hand normal contact of relay 265 and the interrupter 266 to ground. The operation of relay 235 releases relay 273, removing battery from the signaling circuit extending from office Z to office Y, and when the impulse-sending interrupter 266 disengages the grounded segment thereof, relay 236 is released but relay 235 remains locked over a circuit traced therefor.

Relay 246 then operates when interrupter 266 engages its next grounded segment over a circuit extending from battery through the left-hand normal contact of relay 265, the winding of relay 246, the right-hand normal contact of relay 245, the left-hand normal contact of relay 236, the right-hand alternate contact of relay 235, the left-hand

normal contact of relay 226, the right-hand alternate contact of relay 225, the left-hand normal contact of relay 216, the right-hand alternate contact of relay 215, the left-hand alternate contact of relay 264, the right-hand normal contact of relay 265, and the interrupter 266 to ground. Relay 273 again operates, the circuit therefor being traced from battery through the left-hand normal contact of relay 265, the winding of relay 273, the lower normal contact of relay 247 to the right-hand normal contact of relay 245 where it joins the circuit traced for relay 246. In operating, relay 246 causes the operation of relay 245 over a circuit extending from battery through the left-hand normal contact of relay 265, the middle alternate contact of relay 246 and the middle normal contact and winding of relay 245 to ground. Relay 245 locks over a circuit extending from battery through the left-hand normal contact of relay 265 and the left-hand alternate contact and winding of relay 245 to ground. The opening of the right-hand normal contact of relay 245 causes the release of relay 273, thereby removing the battery 259 from operative association with the signaling circuit extending from office Z to office Y. Upon the disengagement of the grounded segment of interrupter 266, relay 246 is released but relay 245 remains locked over a circuit traced for that purpose. When the interrupter 266 engages the next grounded segment thereof, relay 256 is operated over a circuit extending from battery through the left-hand normal contact of relay 265, the winding of relay 256, the right-hand normal contact of relay 255, the left-hand normal contact of relay 246, the right-hand alternate contact of relay 245, the left-hand normal contact of relay 236, the right-hand alternate contact of relay 235, the left-hand normal contact of relay 226, the right-hand alternate contact of relay 225, the left-hand normal contact of relay 216, the right-hand alternate contact of relay 215, the left-hand alternate contact of relay 264, the right-hand normal contact of relay 265 and the interrupter 266 to ground. Relay 273 also operates at this time over a circuit extending from battery through the left-hand normal contact of relay 265, the winding of relay 273, the lower normal contact of relay 257 to the right-hand normal contact of relay 255 where it joins the circuit traced for relay 256. In operating, relay 256 causes the operation of relay 255 over a circuit extending from battery through the left-hand normal contact of relay 265, the middle alternate contact of relay 256 and the middle normal contact and winding of relay 255 to ground. Relay 255 thereupon locks over a circuit extending from battery through the left-hand normal contact of relay 265 and the left-hand alternate contact and winding

of relay 255 to ground. Relay 256 also locks over a circuit extending from battery through the left-hand normal contact of relay 265, the winding and left-hand alternate contact of relay 256, the right-hand alternate contact of relay 255, the left-hand normal contact of relay 246, the right-hand alternate contact of relay 245, the left-hand normal contact of relay 236, the right-hand alternate contact of relay 235, the left-hand normal contact of relay 226, the right-hand alternate contact of relay 225, the left-hand normal contact of relay 216, the right-hand alternate contact of relay 215, the left-hand alternate contact of relay 264, the right-hand normal contact of relay 265 and the interrupter 266 to ground. Relay 273 releases upon the operation of relay 255 and relay 256 releases when the grounded segment of interrupter 266 is disengaged. However, relay 255 remains in an operated condition over a locking circuit traced therefor.

When the interrupter engages the next grounded segment a circuit is completed extending from battery through the winding and middle normal contact of relay 265, the left-hand normal contact of relay 256, the right-hand alternate contact of relay 255, the left-hand normal contact of relay 246, the right-hand alternate contact of relay 245, the left-hand normal contact of relay 236, the right-hand alternate contact of relay 235, the left-hand normal contact of relay 226, the right-hand alternate contact of relay 225, the left-hand normal contact of relay 216, the right-hand alternate contact of relay 215, the left-hand alternate contact of relay 264, the right-hand normal contact of relay 265 and the interrupter 266 to ground. Relay 265 operates over the circuit just traced and locks during the continued engagement of the grounded segment of the interrupter 266 over a circuit extending from battery through the winding and left-hand alternate contact of relay 265 and the interrupter 266 to ground. The opening of the left-hand normal contact of relay 265 removes the battery from connection with the locking circuits for relays 215, 225, 235, 245, 255 and 264, while the opening of the right-hand normal contact of relay 265 removes the interrupter from association with the operating circuits of stepping relays 216, 226, 236, 246 and 256. The locking relays thereupon release and relay 262 also releases due to the removal of the grounded connection from the operating circuit thereof.

The various impulses thus transmitted over the signaling circuit from office Z to office Y, cause the operation of relay 180 in a manner similar to that described in connection with relay 170 upon the receipt of the originating signals from office X, so that the signaling impulses are repeated through the office Y causing the operation of relays 173

and 174 in a manner to correspond to the relays 273 and 274 respectively at office Z. The operation of relay 180 in response to the receipt of signaling impulses also causes the 5 series of operations of relays 113, 114, 123, 124, 133, 134, 143, 144, 153, 154 and 192 in a manner similar to that described in the transmission of the calling signals from office X. The operation of the relays 173 and 10 174 selectively connect the batteries 159 and 169 with the signaling circuit extending from office Y to office X to cause corresponding responses of the polar relay 70 at office X. In response to the first operation of 15 relay 70 a circuit is completed from battery through the left-hand normal contact of relay 60, the winding of relay 13, the right-hand normal contact of relay 14, the right-hand normal contact of relay 60, the winding 20 of relay 61, and the lower contact of relay 70 to ground. Relays 13 and 14 are energized and locked in the same manner as described in connection with relays 213 and 214. Relay 61 in operating in 25 this circuit causes the operation of relay 12 over a circuit extending from battery through the left-hand normal contact of relay 60, the contact of relay 61, the winding of relay 12, the lower left-hand 30 alternate contact of relay 13, and the right-hand alternate contact of relay 14 where it joins the circuit previously traced for relay 13. Therefore, during the continuation of the first signaling impulse, relay 35 12 remains operated completing a circuit extending from the source of alternating current through the lower alternate contact of relay 12, the ring contacts of jacks 10 and plug 1, the lower normal contact of key 3 40 of the link circuit associated with line A at office X, the left-hand winding of relay 6, the condenser 7, the upper normal contact of key 3, the tip contacts of plug 1 and jack 10 and the upper alternate contact of 45 relay 12 to ground. Relay 6 in operating in response to the current flowing over this circuit causes the lighting of supervisory lamp 5 over a circuit extending from battery through the contact of relay 2, the local 50 normal contact of key 4, the lower contact of relay 6 and the lamp 5 to ground. Relay 6 also locks over a circuit extending from battery through the contact of relay 2, the local normal contact of key 4 and the upper 55 contact and right-hand winding of relay 6 to ground. Upon the cessation of the impulse, relays 12 and 61 release. Upon the receipt of the next succeeding impulse, relay 70 closes its upper contact and a circuit is 60 completed extending from battery through the left-hand normal contact of relay 60, the winding of relay 23, the right-hand normal contact of relay 24, the left-hand normal contact of relay 13, the right-hand alternate 65 contact of relay 14, the right-hand normal contact of relay 60 and the upper contact of 70 relay 70 to ground. Relay 23 in operating causes the operation of relay 24 over a circuit extending from battery through the left-hand normal contact of relay 60, the right-hand alternate contact of relay 23 and the left-hand normal contact and winding of relay 24 to ground. Relay 24 locks over a circuit extending from battery through the left-hand normal contact of relay 60 and the left-hand alternate contact and winding of relay 24 to ground. Relay 23 also locks through its winding and left alternate contact and releases upon the cessation of the 75 impulse but relay 24 remains locked over the circuit described therefor. The third impulse being of the same polarity as that of the second causes relay 70 to close its upper contact completing a circuit from battery through the left-hand normal contact of 80 relay 60, the winding of relay 33, the right-hand normal contact of relay 34, the left-hand normal contact of relay 23, the right-hand alternate contact of relay 24, the left-hand normal contact of relay 13, the right-hand alternate contact of relay 14, the right-hand normal contact of relay 60 and the upper contact of relay 70 to ground. Relay 34 thereupon operates over a circuit extending 85 from battery through the left-hand normal contact of relay 60, the right-hand alternate contact of relay 33 and the left-hand normal contact and winding of relay 34 to ground. Upon the cessation of this impulse relays 70 and 33 release but relay 34 remains locked 90 independently thereof. The fourth impulse being of the same polarity as of the third causes relay 70 to again close its upper contact to complete a circuit from battery through the left-hand normal contact of relay 60, the winding of relay 43, the right-hand normal contact of relay 44, the left-hand normal contact of relay 33, the right-hand alternate contact of relay 34, the left-hand normal contact of relay 23, the right-hand alternate contact of relay 23, the left-hand normal contact of relay 13, the right-hand alternate contact of relay 14, the right-hand normal contact of relay 60 and the upper contact of relay 70 to ground. Relay 44 then operates over a circuit extending 100 from battery through the left-hand normal contact of relay 60, the right-hand alternate contact of relay 43, and the left-hand normal contact and winding of relay 44 to ground. Relay 44 then locks over a circuit extending from battery through the left-hand normal contact of relay 60 and the left-hand alternate contact and winding of relay 44 to 105 ground. Relay 43 releases upon the release of relay 70 following the cessation of the impulse but relay 44 remains locked over the circuit traced therefor. The fifth impulse being of the same polarity as the preceding one causes relay 70 to again close its 110 115 120 125 130

upper contact and to complete a circuit from battery through the left-hand normal contact of relay 60, the winding of relay 53, the right-hand normal contact of relay 54, the left-hand normal contact of relay 43, the right-hand alternate contact of relay 44, the left-hand normal contact of relay 33, the right-hand alternate contact of relay 34, the left-hand normal contact of relay 23, the right-hand alternate contact of relay 24, the left-hand normal contact of relay 13, the right-hand alternate contact of relay 14, the right-hand normal contact of relay 60 and the upper contact of relay 70 to ground. Relay 54 thereupon operates over a circuit extending from battery through the left-hand normal contact of relay 60, the right-hand alternate contact of relay 53 and the left-hand normal contact and winding of relay 54 to ground. Relay 54 thereupon locks over a circuit which may be traced from battery through the left-hand normal contact of relay 60 and the left-hand alternate contact and winding of relay 54 to ground. Relay 53 is locked but upon the cessation of the impulse it releases. Relay 54 remains locked independently thereof. Upon the release of relay 53 a circuit is completed from battery through the winding and middle normal contact of relay 60, the right-hand normal contact of relay 53, the middle alternate contact of relay 54, the normal contact of relay 43, the right-hand alternate contact of relay 44, the normal contact of relay 33, the right-hand alternate contact of relay 34, the normal contact of relay 23, the right-hand alternate contact of relay 24, the normal contact of relay 13, the right-hand alternate contact of relay 14, the right-hand alternate contact of relay 54 and the left-hand normal contact of relay 53 to ground. Relay 60 operating in response to the current flowing through this circuit removes battery from the locking circuits of relays 14, 24, 34, 44 and 54 causing their release, and the opening of the middle normal contact of relay 60 prevents the reoperation of relay 53, so that upon the cessation of the impulses the receiving apparatus associated with the line circuits A, B and C at office X returns to normal.

In a similar manner upon the completion of the conversation over line circuit B, the operator at office Z actuates ringing key 203 of the link circuit E associated with the line circuit B at office Z. A circuit is thereby completed extending from the source of alternating current through the lower alternate contact of ringing key 203, the ring contacts of plug 201 and jack 220, the lower normal contact of relay 222, the upper winding of relay 227, the condenser 229 and the upper normal contact of relay 222 to ground. Relay 227 operates in response to the current flowing through this circuit and

locks over a circuit extending from battery through the winding of relay 262, the left-hand normal contact of relay 225, the right-hand normal contact of relay 226 and the upper alternate contact and lower winding of relay 227 to ground. The ringing key is again released by the operator and relay 262 operates to prepare a circuit for relay 264 so that when the continuously rotating pickup interrupter 263 reaches the next grounded segment thereof, relay 264 operates over a circuit extending from battery through the left-hand contact of relay 265, the winding and the right-hand normal contact of relay 264, the contact of relay 262 and the interrupter 263 to ground. Relay 264 in operating locks over the circuit previously traced therefor including the right-hand alternate contact thereof, so that when impulse-sending interrupter 266 reaches the next grounded segment, relays 273 and 216 operate over circuits traced therefor in connection with the transmission of the disconnect signal over line circuit A, and initiate the series of operations of relays 215, 226, 225, 236, 235, 246, 245, 256, 255 and 265 as described in connection with the previous instance with the exception that relay 274 instead of relay 273 operates simultaneously with relay 226, so that the second impulse transmitted over the signaling circuit from office Z to office Y is of the opposite polarity as compared with that transmitted in connection with the disconnect signaling impulse for line circuit A. Relay 227 releases in the same manner as relay 217 to reestablish the continuity of the line conductors. As in the previous instance the operation of relay 265 causes the release of the locked relays as well as the release of relays 264 and 262. These impulses are received at office Y and cause operations of relay 180 thereat to initiate the usual stepping operations of relays 113, 114, 123, 124, 133, 134, 143, 144, 153, 154 and the operation of relay 192 which releases the locked relays of the previously mentioned set in the same manner as described in the previous instance. The impulses are also repeated through the agency of relay 180 as it controls relays 173 and 174 so that similar impulses are impressed upon the signaling circuit extending from office Y to office X where they are received by relay 70. The operation of relay 70 in response to these impulses causes the operations of relays 13, 14, 22, 61, 23, 24, 33, 34, 43, 44, 53, 54, and 60, the operation of the latter relay, as in the other case, unlocking the relays which have been previously locked. However, relays 61 and 12 do not respond upon the first impulse received, but relays 61 and 22 respond upon the second impulse due to the reversed polarity of such impulse, so that relay 61 operates over a circuit extending from battery through the left-hand normal contact 130

of relay 60, the winding of relay 23, the right-hand normal contact of relay 24, the normal contact of relay 13, the right-hand alternate contact of relay 14, the right-hand 5 normal contact of relay 60, the winding of relay 61 and the lower contact of relay 70 to ground. Relays 23 and 24 then energize as before. Relay 22 thereupon operates over a circuit extending from battery through 10 the left-hand normal contact of relay 60, the contact of relay 61, the winding of relay 22, the lower left-hand alternate contact of relay 23, the right-hand alternate contact of relay 24, the normal contact of 15 relay 13, the right-hand alternate contact of relay 14, the right-hand normal contact of relay 60, the winding of relay 61 and the lower contact of relay 70 to ground. Relays 61 and 22 release upon the cessation of 20 the impulse, but during the period in which relay 22 is operated a momentary circuit is completed which extends from the source of alternating current through the lower alternate contact of relay 22, the ring contacts 25 of jack 20 and plug 1, the lower normal contact of key 3, the left-hand winding of relay 6, the condenser 7, the upper normal contact of key 3, the tip contacts of plug 1 and jack 20 and the upper alternate contact 30 of relay 22 to ground. In response to the current flowing over this circuit, relay 6 operates to cause the lighting of supervisory lamp 5 and locks in a manner as described in connection with the previous instance. 35 In response to the illumination of supervisory lamp 5 of the link circuit D associated with line circuit B, the operator at office X removes the plug 1 from the jack 20, thereby restoring all apparatus in the 40 link circuit D to normal. After the last impulse in the chain relay 53 releases and relay 60 operates as before to restore relays 14, 24, etc. Relay 67 does not release due to the presence of the plug 1 of the third link 45 circuit D in the jack 30.

Upon the completion of the conversation over line circuit C, the operator at office Z actuates ringing key 203 of the third link circuit E thereat to complete a circuit extending from the source of alternating current through the lower alternate contact of key 203, the ring contacts of plug 201 and jack 230, the lower normal contact of relay 232, the upper winding of relay 237, 50 the condenser 239, the upper normal contact of relay 232, the tip contacts of jack 230 and plug 201 and the upper alternate contact of key 203 to ground. Relay 237 responding to the current flowing through 55 this circuit locks over a circuit extending from battery through the left-hand normal contact of relay 265, the winding of relay 262, the left-hand normal contact of relay 235, the right-hand normal contact of relay 236 and the upper alternate contact and 60 lower winding of relay 237 to ground. Relay 262 operating by virtue of this circuit prepares a circuit for relay 264 so that when the pick-up interrupter 263 engages the next grounded segment, relay 264 is operated over a circuit as previously traced therefor in connection with the other instances and becomes locked in an operated condition over an obvious circuit. Therefore, upon the engagement of the impulse-sending interrupter 266 with a grounded segment, relays 216, 215, 226, 225, 235, 236, 246, 245, 256, 255, 265, 262, 264, and 237 operate and release as described in connection with the previous instances. However, due to the operation of relay 237, relay 274 instead of relay 273 operates simultaneously with relay 236, thereby causing a reversed current impulse to be sent over the signaling circuit extending from office Z to office 75 Y. The transmitted impulses are received at office Y and cause the operation of relay 180 which, as in the previous instances, performs the dual function of causing the usual sequence of operations of relays 113, 114, 123, 124, 133, 134, 143, 144, 153, 154, 192 and 193 and of repeating such impulses through the agency of relays 173 and 174 into the signaling circuit extending from office Y to office X. Such impulses being received at office X cause the operation of relay 70 as in the previous case which, in operating in response to this series being transmitted, causes a similar operation of 80 relays 13, 14, 23, 24, 32, 61, 33, 34, 43, 44, 53 and 54 followed by the operation of relay 60 which releases the relays previously locked. However, in this case relay 32 is operated by relay 61 in response to the third impulse which is received instead of relay 22 or relay 12, as in the previous instances. Relay 61 is operated over a circuit extending from battery through the left-hand normal contact of relay 60, the winding of relay 33, the right-hand normal contact of relay 34, the left-hand normal contact of relay 23, the right-hand alternate contact of relay 24, the left-hand normal contact of relay 13, the right-hand alternate contact of relay 14, the right-hand normal contact of relay 60, the winding of relay 61, and the 85 90 95 100 105 110 115 120 125 130

lower contact of relay 70 to ground. Therefore, during the continuation of the third impulse, relay 32 is operated to complete a momentary circuit extending from the 5 source of alternating current through the lower alternate contact of relay 32, the ring contacts of jack 30 and plug 1, the lower normal contact of key 3, the left-hand winding of relay 6, the condenser 7, the upper 10 normal contact of key 3, the tip contacts of plug 1 and jack 30 and the upper alternate contact of relay 32 to ground. As in the previous instances, supervisory relay 6 responds to such current causing the illumination 15 of supervisory lamp of the third link circuit D at office X and locks in an operated condition.

20 *Operator at office X removes the plug of the third link circuit thereat from the jack of the third line circuit.*

In response to the lighted condition of the supervisory lamp 5 of the third link circuit D at office X, the operator thereat removes 25 the plug 1 of such link circuit from the jack 30, thereby causing the release of relays 2 and 6 and the extinguishment of supervisory lamp 5 of such link circuit as previously described. Due to the removal of the third 30 plug from the third jack of the series, relay 67 releases causing the release of relays 68 and 69, but due to the slow release nature of relay 69, a temporary circuit is established from battery through the normal contact 35 of relay 68, the upper winding of relay 57 and the alternate contact of relay 69 to ground. Relay 57 thereupon operates and locks over a circuit extending from battery through the right-hand normal contact of 40 relay 65, the winding of relay 62, the right-hand normal contact of relay 55, the left-hand normal contact of relay 56 and the middle alternate contact, the lower winding and the upper alternate contact of relay 57 45 to ground. Relay 62 also operates over the circuit just traced, and when the pick-up interrupter 63 engages its next grounded segment, relay 64 operates over a circuit similar to that previously traced therefor 50 and locks over an obvious circuit. Therefore when impulse-sending interrupter 66 engages the next grounded segment, the series of operations of relays 16, 15, 26, 25, 36, 35, 46, 45, 56, 55 and 65 are initiated in the 55 same manner as previously described. Relay 65 in operating also causes the release of the locked relays and of relays 62 and 64. In this instance relay 74 instead of relay 73 operates simultaneously with relay 56 so 60 that an impulse of reversed polarity is transmitted over the signaling circuit extending from office X to office Y in connection with the fifth impulse. As in the previous cases, the relay 170 at office Y responds to the 65 impulses and performs the dual function of

causing the series of operations of relays 113, 114, 123, 124, 133, 134, 143, 144, 153, 154, 192, and 193, and also through the agency of relays 183 and 184 repeats such impulses into the signaling circuit extending from office Y to office Z. However, in connection with the fifth impulse received at office Y, relay 193 operates over a circuit extending from battery through the left-hand normal contact of relay 192, the winding of relay 153, the middle normal contact of relay 154, the left-hand normal contact of relay 143, the right-hand alternate contact of relay 144, the left-hand normal contact of relay 133, the right-hand alternate contact of relay 134, 70 the left-hand normal contact of relay 123, the right-hand alternate contact of relay 124, the left-hand normal contact of relay 113, the right-hand alternate contact of relay 114, the right-hand normal contact of relay 192, the winding of relay 193 and the left-hand lower contact of relay 170 to ground. During 75 the continuation of the fifth impulse, when relay 193 is operated, relay 191 is operated over a circuit extending from battery through the left-hand normal contact of relay 192, the contact of relay 193, the winding of relay 191 to the right-hand normal contact of relay 154, and from thence through 80 contacts of relays 143, 144, 133, 134 etc., the right-hand normal contact of relay 192, the winding of relay 193 and the left-hand lower contact of relay 170 to ground. The response of relay 191 due to the current flowing through this circuit opens the locking circuit of and releases relay 190, thereby removing the grounded connection from the repeaters RA, RB and RC associated with 85 the line circuits A, B and C. 90

These impulses being received at office Z causes the operation of relay 270 thereat, which in turn causes the series of operations of relays 213, 214, 223, 224, 233, 234, 243, 244, 253, 254 95 260 and 261 as described in connection with the initiation of the calls over the various lines. However due to the fact that all of the first three impulses are of the same polarity, no signal is produced at the office Z in response to the series of the operations of the relays 43, 44, 53 and 54 and therefore no material effect is produced upon the system. Upon the withdrawal of the plugs 201 of first and second link circuits D at office Z upon the completion of the 100 conversation over the lines, no material effect is produced and upon the withdrawal of plug 201 of the third link circuit D from the jack 230, relay 267 is released to cause the release of relays 268 and 269 and due 105 to the slow release nature of relay 269, relay 257 is operated over the circuit temporarily established from battery through the normal contact of relay 268, the upper winding of relay 257 and the alternate contact of 110 115 120 125 130

- relay 269 to ground. Relay 257 thereupon becomes locked and relay 262 operates over a circuit extending from battery through the left-hand normal contact of relay 265, the 5 winding of relay 262, the left-hand normal contact of relay 255, the right-hand normal contact of relay 256 and the middle alternate contact, lower winding and upper alternate contact of relay 257 to ground. Thus 10 when the pick-up interrupter 263 reaches the next grounded segment, relay 264 operates over a circuit previously traced therefor and locks in an operated condition over an obvious circuit. When impulse-sending 15 interrupter 266 engages its next grounded segment, the series of operations of relays 216, 215, 226, 225, 236, 235, 246, 245, 256, and 255 are initiated as previously described. This series of operations is followed in the 20 same manner by the operation of relay 265 which causes the release of relay 264, and relay 257 releases in a manner similar to that described for relay 47. This set of operations causes the operation of relays 273 and 25 274 in the manner previously described in connection with the transmission of the disconnect signals, except that relay 274 instead of relay 273 operates in connection with the operation of relay 256 so that the 30 fifth impulse transmitted over the signaling circuit from office Z to office Y is caused by battery 269' instead of 259. These impulses are received as in the previous instances at office Y and cause the operation of relay 180 35 as mentioned in the other cases, which performs the dual function of causing the set of operations as previously described for relays 113, 114, 123, 124, 133, 134, 143, 144, 153, 154, 192 and 193 as well as through the 40 agency of relays 173 and 174 repeating such impulses into the signal circuit extending from office Y to office X. The operation of the relays at office Y produces no material effect upon the system since relay 190 was 45 released in connection with the impulse transmitted from office X to office Y. Such impulses are received at office X, as previously described, and cause the same series of operations of the receiving relays thereat, but no other effect is produced upon the 50 system due to the fact that no signaling relays have been operated so that the impulses are of the same character and no link circuits are associated with the line circuits 55 thereof. Therefore, upon the completion of the series of operations of the relays at office X all the apparatus of the system has been restored to normal as shown on the drawings.
- 60 What is claimed is:
1. In a telephone system, a plurality of transmission lines, a signaling circuit connected to certain of said lines, an impulse mechanism including a plurality of relays common to said lines and arranged in groups,
  2. In a telephone system, a plurality of transmission lines, a signaling circuit connected to certain of said lines, an impulse mechanism including a plurality of relays common to said lines, another group of relays cooperating with the first named groups, each relay of the other group being individual to one of said lines and operable after a call is initiated on its line, means for controlling the operation of the first named groups of relays, and means controlled by said groups of relays and responsive to the operation of the last named means for transmitting successive signals of different polarities over said signaling circuit to indicate a particular line taken for use.
  3. In a telephone system, a plurality of transmission lines, a signaling circuit connected to certain of said lines, an impulse mechanism including a plurality of relays common to said lines and operable each time a call is initiated on one of them, a group of relays cooperating with said plurality of relays, each relay of said group being individual to one of said lines and operable after a call is initiated on its line, a continuously driven interrupter for controlling the operation of said plurality of relays, and means controlled by all of said relays and responsive to the operation of said interrupter for transmitting successive signals of different polarities over said signaling circuit to indicate a particular line taken for use.
  4. In a telephone system, a plurality of transmission lines, a signaling circuit connected to certain of said lines, an impulse mechanism including a plurality of relays arranged in groups, means for operating said groups of relays in succession, another group of relays cooperating with the first named groups of relays, each of the relays of said other group being individual to one of said lines and operable after a call is initiated on its line, and means controlled by said groups of relays and responsive to the operation of the first named means for transmitting a series of impulses of different polarities over said signaling circuit to indicate a particular line taken for use.
  5. In a telephone system, a plurality of transmission lines, a signaling circuit connected to certain of said lines, an impulse mechanism including a plurality of groups of relays, means for operating said groups of relays in succession, another group of relays cooperating with the first named groups, each of the relays of said other group being individual to one of said lines and responsive to alternating current applied to its line, and means controlled by said groups of relays and responsive to the operation of the first named means for transmitting a series of impulses of different polarities over said signaling circuit to indicate a particular line taken for use.
  6. In a telephone system, a plurality of transmission lines, a signaling circuit connected to certain of said lines, an impulse mechanism including a plurality of groups of relays, means for operating said groups of relays in succession, another group of relays cooperating with the first named groups, each of the relays of said other group being individual to one of said lines and responsive to alternating current applied to its line, and means controlled by said groups of relays and responsive to the operation of the first named means for transmitting a series of impulses of different polarities over said signaling circuit to indicate a particular line taken for use.

transmission lines, a signaling circuit connected to certain of said lines, an impulse mechanism including groups of relays, an interrupter for operating said relays in succession, another group of relays cooperating with the first named groups, each of the relays of said other group being individual to one of said lines and operable after a call is initiated on its line, and means controlled by said groups of relays and responsive to the operation of said interrupter for transmitting a series of impulses of different polarities over said signaling circuit to indicate a particular line taken for use.

6. In a telephone system, a plurality of transmission lines, telephone repeaters associated with said lines, a signaling circuit connected to certain of said lines and an impulse mechanism connected with said lines and operable when any one of them is taken for use to transmit a series of impulses of different polarities over said signaling circuit to operate said repeaters and to transmit another series of impulses modified with respect to the first named series to indicate the particular line over which a call is initiated.

7. In a telephone system, distant offices, an intermediate office, telephone repeaters at said intermediate office, a plurality of transmission lines interconnecting said offices, a signaling circuit connected to certain of said lines, and an impulse mechanism at each distant office operable to transmit a series of impulses over said signaling circuit to the intermediate office to operate said repeaters, and operable when any one of the lines is taken for use to transmit a second series of impulses modified with respect to the first named series to indicate at the other distant office the particular line over which a call is initiated.

8. In a telephone system, distant offices, an intermediate office, telephone repeaters at said intermediate office, a plurality of transmission lines interconnecting said offices, a signaling circuit connected to certain of said lines, and an impulse mechanism at one distant office operable to transmit impulses of different polarities to said intermediate office to operate the telephone repeaters thereat, said mechanism being also operable when one of the lines is taken for use to transmit over said signaling circuit to the other distant office a second series of impulses modified with respect to the first series to indicate at said other distant office the line taken for use.

9. In a telephone system, distant offices, an intermediate office, physical and phantom lines interconnecting said distant and intermediate offices, repeaters associated with said lines at said intermediate office, a signaling circuit connected to the physical lines, an impulse mechanism at each distant office

operable when a call is initiated on any one of said lines to transmit a series of impulses of different polarities over said signaling circuit to render said repeaters effective, means for controlling each impulse mechanism whereby to cause the same to transmit a second series of impulses modified with respect to the first series, and means responsive to said second series of impulses for indicating the particular line over which the call has been initiated.

10. In a telephone system, distant offices, an intermediate office, physical and phantom lines interconnecting said offices, a signaling circuit connected to said physical lines, repeaters associated with said lines at said intermediate office, an impulse mechanism at one of said distant offices operable upon the initiation of a call to transmit a series of impulses of different polarities to render effective the repeaters at said intermediate office, means at the last named distant office for controlling the operation of said impulse mechanism to cause the same to transmit another series of impulses over said signaling circuit when one of said lines is taken for use, the second series of impulses being modified with respect to the first series, and another means for controlling the operation of said impulse mechanism to cause the same to transmit a third series of impulses modified with respect to the first two-named series when another line is taken for use contemporaneously with the first-named line.

11. In a telephone system, a plurality of transmission lines, repeaters associated with said lines, and an impulse transmitting mechanism operable in response to the initiation of a call on any one of said lines to transmit over said lines a series of impulses to operate said repeaters and to transmit another series of impulses to identify the line taken for use.

12. In a telephone system, a plurality of transmission lines, repeaters associated with said lines, and an impulse transmitting mechanism operable in response to the initiation of a call on any one of said lines to transmit over said lines a series of impulses to operate said repeaters and to transmit another series of impulses modified with respect to the first series to identify the line taken for use.

13. In a signaling system, a plurality of transmission lines, telephone repeaters associated with said lines, a signaling circuit common to said lines, and means responsive to a change in condition on one of said lines to transmit a series of impulses to operate said repeaters and responsive to another change in condition of said line to transmit another series of impulses to identify said line.

14. In a signaling system, a plurality of

- transmission lines, telephone repeaters associated with said lines, a signaling circuit common to said lines, and means responsive to a change in condition on one of said lines to transmit a series of impulses to operate said repeaters and responsive to another change in condition of said line to transmit another series of impulses modified with respect to the first series to identify said line.
15. In a signaling system, a plurality of transmission lines, telephone repeaters associated with said lines, a signaling circuit common to said lines, and means responsive to a change in condition on one of said lines to transmit a series of impulses to operate said repeaters and responsive to another change in condition of said line to transmit a second series of impulses to identify said line, said means being also responsive to a third change in condition of said line to transmit a third series of impulses to disable said repeaters.
20. In a signaling system, a plurality of transmission lines, telephone repeaters associated with said lines, a signaling circuit common to said lines, and an impulse mechanism operable when any one of said lines is taken for use to transmit a series of impulses over said signaling circuit to operate said repeaters and to transmit another series of impulses modified with respect to the first named series to indicate the particular line over which a call is initiated.
25. 17. In a signaling system, distant offices, a repeating office, physical and phantom lines interconnecting said offices, repeaters at said repeating office associated with said physical and phantom lines, and means at said distant offices for rendering operative the repeaters associated with said physical and phantom lines.
30. 18. In a signaling system, distant offices, a repeating office, physical and phantom lines interconnecting said offices, repeaters at said repeating office associated with said physical and phantom lines, and means for transmitting impulses from said distant offices over said signaling path for rendering operative the repeaters associated with said physical and phantom lines.
35. 19. In a signaling system, distant offices, a repeating office, physical and phantom lines interconnecting said offices, repeaters at said repeating office associated with said physical and phantom lines, and means for transmitting other impulses to identify said lines.
40. 20. In a signaling system, distant offices, a repeating office, physical and phantom lines interconnecting said offices, a signaling path common to said lines, repeaters at said repeating office associated with said physical and phantom lines, and means for transmitting impulses from said distant offices over said signaling path for rendering operative the repeaters associated with said physical and phantom lines.
45. 21. In a signaling system, distant offices, a repeating office, physical and phantom lines interconnecting said offices, a repeater at said repeating office associated with said phantom line, and means at said distant offices for rendering operative said repeater.
50. 22. The method which comprises operating telephone repeaters by a series of impulses when a transmission line is taken for use, and transmitting another series of impulses to identify said line.
55. 23. The method which comprises operating telephone repeaters by a series of impulses when a transmission line is taken for use, and transmitting another series of impulses modified with respect to the first named series to identify said line.
60. In witness whereof, I hereunto subscribe my name this 27th day of December, A. D. 1919.

ROY D. CONWAY.
